J. THOMSON

DISK FOR WATER METERS

Original Filed March 3, 1923

INVENTOR:

John Thomson

UNITED STATES PATENT OFFICE.

JOHN THOMSON, OF BROOKLYN, NEW YORK.

DISK FOR WATER METERS.

Application filed March 3, 1923, Serial No. 622,700. Renewed February 12, 1925.

To all whom it may concern:

Be it known that I, JOHN THOMSON, a citizen of the United States, and a resident of the borough of Brooklyn, city and State 5 of New York, have invented Improvements in Disks for Water Meters, of which the following is a specification.

This invention relates to disk water meters, consisting of an improvement in the 10 disk itself; and its objects are to decrease the frictional resistance and increase the endurance thereof. As herein employed, the unitary term "disk" includes its ball, being the adopted nomenclature of common parlance.

15 It is deemed within the truth to state that nine-tenths of the disks in water meters, of which many millions are now in use, are formed of hard-rubber, machined from rough stock. Their coefficient of friction 20 is relatively low in that, when acting against bronze or brass, water somewhat serves as a lubricant.

It goes without saying that even a nominal diminution of the present frictional coefficient of disks, or "the disk-action," would both increase the registration of meters at 25 the sensibility rates of flow and enhance their endurance when run rapidly and for long periods of time. To that end, disks 30 have been made in which some minor portion of the compound is pulverized graphite, thoroughly pre-mixed in the mass. Thus, it will be apparent that but a nominal part of the graphitic content will be in evidence at 35 the superficial surfaces of the disk, which is the object of introducing it; moreover, the unctuous characteristic of graphite is detrimental to its binding efficiency and sacrifice of tensile strength ensues.

40 In the present instance a thin film plating or sheathing of pure graphite, preferably in the form of a deflocculated dust, is primarily applied to the surfaces of the rubber in such manner and with such effect that the 45 graphite is as completely imprisoned and pressure-welded to the surfaces as if it had been mixed with and permeated the compound.

The accompanying drawings, which form 50 a part of this specification, are introduced to assist in visualizing a preferred process or maneuver for realizing the benefits of this invention.

Figure 1 is a plan view of a water meter disk in which the usual diaphragm slot is indicated in dotted lines; 55

Figure 2 comprises a half edge elevation and a half transverse section of the disk at the state when the graphitic dust is first applied thereto, that is in a pigmental free 60 state; and,

Figure 3 also comprises a half edge elevation and a half transverse section of the same disk, as in Figure 2; but at that state of the maneuver when the graphitic dust 65 has been permanently pressure-welded upon and embedded in its surfaces.

The preferred grade of graphite for the purpose hereof is that known by the trademark of "Aquadag", produced by the electric furnace process of Acheson, whose state of comminution is unique in the art, bordering upon the domain of the "molecular." It is wholly devoid of earthly grit and, in a practical sense, is "pure." When water—preferably distilled—is mixed with this dust it can be brushed, smeared or sprayed upon surfaces as in the instance of paint or paste. Now, when a surface of any material 70 is made very clean, as by means of alcohol; is coated with this hydro-graphitic dope; held until the free water evaporates and is then somewhat rubbed with a soft cloth its intimacy of adherence to the surface simulates that of glue or varnish. This is really 75 an astonishing result; for, as there is no binder other than water and even it has been evacuated, the justifiable assumption is that the graphite would reappear as dust; but it does not. Perhaps it might be termed an 80 articulated film. The reasons for this phenomenon are more or less hypothetical and 85 need not be here discussed.

In certain cases, as when the highest state 90 of purity in the applied graphite is not essential, a minor quantity of sodium silicate may be advantageously added to the dope.

The thickness of the pigmental graphitic 95 films which can thus be readily applied to surfaces range from a few ten-thousandths of an inch upwardly.

In the realization hereof, the first step in the maneuver is to provide a pre-formed, hard rubber disk A, Figure 2, having a sprue as b, coating the surfaces with a film 100 of graphite as c, c¹, C², according to the pro-

cedure just set forth. The dimensions of the disk are to be such that it can be freely entered and clamped within a molding-die, here indicated by the dotted outline B, the 5 free space denoted around the disk being exaggerated over the requirements of practice; which need not exceed a few thousandths of an inch.

The second step is to heat the molding 10 die to a temperature at which the hard rubber disk and sprue therein shall become plastic, that is a condition which may be characterized as pasty, somewhat like heated wax, and flowable, under pressure, as in the 15 case of fluids.

The third step is to apply pressure upon the conical head, d , of the sprue, causing it to move downwardly, displace the underlying main volume of rubber and compelling 20 it to flow radially, whereby to completely fill the die-cavity.

The fourth step is to permit the disk to cool in place, the forming pressure being meantime maintained.

25 Thus, the removed disk, Figure 3, will have acquired the exact volume and dimensions of the die-cavity and be, in fact, a finished product except as to the removal of the tit e , which represents the material in 30 excess of that required to compensate for the lesser dimensions of the pre-formed disk.

The present relevancy of the aforesaid 35 steps is to publicly disclose adequate ways and means for realizing the paramount feature of this invention. Thus, under the conditions herein shown and described, the pressure which is readily impartable to the plastic but highly viscous rubber is limited 40 only by the resisting capacity of the mold. As the rubber is rolled radially outward the applied and persistently adherent film of graphite is correspondingly compressed, driven into the superficial surfaces of the 45 disk, and burnished to whatever degree of smoothness may have been imparted to the contacting surfaces of the die.

It is no figure of speech to state that the 50 superficial surfaces of the disk are considerably impregnated with graphitic dust, the two substances being pressure-welded together. For example, it is as if minute metallic globules, such as zinc-dust, were 55 driven into the plastic rubber which, when solidified, would intimately hold the globules, like gravel in concrete.

Numerous needle-like points and hairlines of rubber may break through the 60 graphite film, but that is a desirable feature; for graphite is thereby imprisoned between vertical "walls" of rubber and securely held against future dislodgement. Hence, the

graphitic film may not be continuous and unbroken; but, as when viewed microscopically, its appearance may simulate that of 65 a crazy-cracked web. Be all this as it may, the material result is a disk of such smoothness, and subtending such a low co-efficient of friction as could only be otherwise attained by forming the disk wholly from 70 solidified graphite, or graphitic-carbon; the cost of which would be prohibitive; its weight objectionable and its strength inadequate.

This graphitic-faced disk, produced in 75 finished dimensions by die-molding, is more readily released after being cooled than when raw or pre-vulcanized rubber directly impinges upon the die-surfaces; which, by avoidance of deformation and saving in 80 time, are in themselves contingent advantages of distinct importance.

By thus diminishing the co-efficient of friction, the sensibility of disk water meters is substantially enhanced and their ultimate 85 endurance is correspondingly increased, yet the cost of realizing these betterments is merely nominal.

It is not deemed necessary to amplify, as by specific enumeration, that this system of 90 graphitically coating hard-rubber, or analogous compounds, is applicable to various articles and uses where diminution of friction is desirable.

What I claim is:

1. A hard-rubber water meter disk having 95 a superficial coating of graphitic dust impressed thereon and therein when the said disk is in a plastic condition.

2. A hard-rubber water meter disk having 100 a superficial coating of highly comminuted graphite primarily applied as a free pigment and thereafter impressed upon and within the disk-surfaces when the hard-rubber is in a plastic condition.

105 3. In disk-action water meters, a hard-rubber disk whose bearing surfaces are coated or plated with films of comminuted graphite, the particles comprising said films being impressed upon and into the superficial surfaces of the hard-rubber when the latter is in a state of plasticity.

110 4. In disk-action water meters, a hard-rubber disk whose bearing surfaces are plated and impregnated with films of comminuted graphite, the particles comprising said films being pressure-welded upon and into superficial surfaces of the hard-rubber 115 when the latter has been heated to a condition characterizable as plastic.

120 This specification signed on the 28th day of February, A. D., 1923.

JOHN THOMSON.
